(57) **CLAIM**

The ornamental design for a dehumidifier, as shown and described.

DESCRIPTION

FIG. 1 is a front perspective view of a dehumidifier showing our new design;

FIG. 2 is a front view thereof;

FIG. 3 is a rear view thereof;

FIG. 4 is a left side elevation view thereof;

FIG. 5 is a right side elevation view thereof;

FIG. 6 is a top view thereof;

FIG. 7 is a bottom view thereof;

FIG. 8 is a rear perspective view thereof;

FIG. 9 is a rear perspective view thereof in an alternate configuration; and,

FIG. 10 is an exploded perspective view thereof in an alternate configuration.

The broken lines illustrating portions of the dehumidifier form no part of the claimed design.
